UNITED STATES PATENT OFFICE.

MAX PASCHEN, OF KÖTHEN, GERMANY.

DOUBLE-KNIFE BOX FOR BEET-ROOT-SLICING MACHINES.

1,040,003.

Specification of Letters Patent.

Patented Oct. 1, 1912.

Application filed July 8, 1911. Serial No. 637,497.

To all whom it may concern:

Be it known that I, MAX PASCHEN, a subject of the Emperor of Germany, residing at 18 Schillerstrasse, Köthen, Anhalt, in the Empire of Germany, have invented certain new and useful Improvements in Double-Knife Boxes for Beet-Root-Slicing Machines, of which the following is a specification.

10 The present invention relates to an improved double knife box for beetroot slicing machines.

In the form of double-knife box heretofore employed and described for example in German Patent No. 85888, dated January 1, 1895, which has already lapsed, the front knife was secured by screws in such a manner as to be displaceable longitudinally beneath the fixed serrated guide-bar or web 15 arranged opposite the rear knife and adapted to guide the beetroots between the front knife and the rear knife. This arrangement entailed numerous disadvantages. In order to obviate these defects, it has been 20 proposed to arrange the front knife between two holding plates, the upper of which is clamped by means of a cylindrically bent projection on a fixed supporting web through the guide bar for the rear knife, the adjustment of the depth of cut being effected by 25 rotating the front knife about the middle axis of the said cylindrical projection. Apart from the disadvantage inherent in the rotatability of the front knife, this construction does not avoid the necessity for 30 the undesirable steep inclination of the front knife to an adequate adjustment and if the knife is to be sufficiently adjustable, that is to say if it is to be used until but little 35 of it is left, would cause a very large interval between the guide bar and the supporting web of the front knife.

In the present invention the arrangement 40 is such that the clamping plate of the front knife serving as counter-piece for the rear knife is tippable about an axis in proximity to its front edge in a manner known in connection with single knife boxes and front knife counter-pieces of double knife boxes 45 and is provided with height adjusting means for its rear upper edge. This arrangement renders it possible to adjust the rear edge of the bearing plate in height independently 50 relatively to the cutting edge of the rear knife without the whole of the front knife

being simultaneously moved forward parallel therewith as would be the case in a construction having the middle beam displaceable vertically and parallel. If an adjusting wedge be arranged beneath the rear end 55 of the bearing plate by tightening the fixing screws of the bearing plate the front knife and the adjusting wedge are simultaneously locked in position so that no special fixing means for the adjusting wedge are necessary. So long as the fixing screws of the bearing plate are not tightened it is possible to alter the height of the cutting edge of the front knife and also of the rear edge of the bearing plate independently of each other 60 as desired. By means of the novel construction the adjustment and fixing is very convenient and the height of the cutting edge relatively to the counter-piece can be adjusted quite independently of each other as 65 regard the front and rear knives.

The invention is illustrated by way of example in the accompanying drawing in which:

Figure 1 is a cross section through the 70 knife box. Fig. 2 is a section on the line A B in Fig. 1 viewed in the direction indicated by the arrow, and Fig. 3 is an enlarged view of the front part of the front knife.

Instead of the front knife *v* being attached to the under side of a transverse web or bar as is usual in this class of apparatus and as shown in the German patent before referred to, the said knife is supported upon a fixed web or abutment *a* and is clamped thereon by the grooved guide-bar *b* of the front knife, by means of a lag screw which is inserted from beneath up through the web, the knife, and the guide-bar. The knife shank is provided with a longitudinal slot, 75 so that the knife may be readily adjusted longitudinally on the web *a*. It is also adapted to be readily detached, and an important advantage is attained by making the grooved guide-bar *b* the clamping means. 80 The knife *v* is held as nearly level or horizontal as practicable it being inclined only about 13° to the horizontal, which angle enables it to cut and slice the beet smoothly and with the least resistance and friction. 85 The front knife *v* is provided on its upper side with a cutting and supporting face *c* and upon its lower side with a cutting face and the upper chamfering or sharpening is 90 twice as long as the lower.

100

105

110

Now as practical experiments have demonstrated, while with the known double knife boxes the chamfering or sharpening of the front knife equally on both sides gave very bad slices and was consequently very undesirable, in practice the surprising fact has been found that in the case of the novel double knife box, the front knife of which is arranged in a fixed slightly inclined position, the slices produced are exceedingly good and far superior to those formed when the sharpening is on one side only. The inclination of the knife to the horizontal is about 13° or as slight as practicable, with the upper bevel arranged parallel to the horizontal. Now in order to render the upper edge of the bearing plate *b* which serves as counter-piece for the rear knife *e* adjustable in height vertically an adjusting wedge *f* is arranged beneath the rear end of the bearing plate *b* so as to be displaceable in a corresponding groove in the supporting web *a*. This adjusting wedge is furnished with a handle *g* which protrudes through an opening *h* in the rear wall of the web *b* so that by means of this handle the wedge *f* can conveniently be adjusted. If after loosening the fixing nuts *i* of the bearing plate the adjusting wedge *f* is moved toward the right hand for example (Fig. 2) the bearing plate *b* tilts about its front edge *k* in simultaneously lifting the rear upper edge *l* which governs the cutting action of the rear knife *e*. On tightening the nuts *i* the front knife *v* and the adjusting wedge *f* which have hitherto also been adjustable are clamped by the pressure of the bearing plate *b*.

As will be apparent from the foregoing explanation the adjustment in height of the rear edge *l* of the bearing plate does not produce any adjustment in the height of the front edge *k* so that there is no risk of the material being cut accumulating against this front edge *k*. It will of course be un-

derstood that the adjusting wedge *f* might also be arranged above the front knife *v*.

What I claim and desire to secure by Letters Patent of the United States is:—

1. In a double knife box for slicing machines, in combination, a supporting web, a front knife carried by said web in a fixed, slightly inclined position, a rear knife, a guide bar for said rear knife, said guide bar disposed on said front knife, and means for adjusting the edge of the guide bar adjacent the rear knife by tilting said guide bar about its opposite edge. 50

2. In a double knife box for slicing machines, in combination, a supporting web, a front knife carried by said web in a fixed, slightly inclined position, a rear knife, a guide bar for said rear knife, said guide bar disposed on said front knife, and a wedge disposed below the rear edge of said guide bar, to raise said edge. 60

3. In a double knife box for slicing machines, in combination, a supporting web, a front knife carried by said web in a fixed, slightly inclined position, a rear knife, a guide bar for said rear knife, said guide bar disposed on said front knife, a wedge disposed below the rear edge of said guide bar, to raise said edge, and means fastening said web, front knife and guide bar in adjusted 70 position. 75

4. In a double knife box for slicing machines, in combination, a supporting web, a front knife carried by said web, displaceable longitudinally with reference to said web, a rear knife, a guide bar for said rear knife, said guide bar disposed on said front knife, and a wedge disposed below the rear edge of said guide bar to raise said edge. 80

In testimony whereof I affix my signature 85 in presence of two witnesses.

MAX PASCHEN.
